UNITED STATES PATENT OFFICE.

ALBERT PATITZ, OF MERIDEN, CONNECTICUT, ASSIGNOR TO THE BRADLEY & HUBBARD MANUFACTURING COMPANY, OF SAME PLACE.

DESIGN FOR A HOLDER FOR LAMP-FOUNTS.

SPECIFICATION forming part of Design No. 24,129, dated March 19, 1895.

Application filed February 18, 1895. Serial No. 538,905. Term of patent 3½ years.

To all whom it may concern:

Be it known that I, ALBERT PATITZ, of Meriden, in the county of New Haven and State of Connecticut, have invented a new Design for a Lamp-Fount Holder, (Case B;) and I do hereby declare the following, when taken in connection with the accompanying drawings and the letters of reference marked thereon, to be a full, clear, and exact description of the same, and which said drawings constitute part of this specification, and represent, in—

Figure 1, a side view of a lamp-fount holder embodying my design; Fig. 2, a top outline view of the same.

This invention relates to a design for a lamp-fount holder, and the design consists in the configuration and ornamentation as shown in the accompanying illustrations.

In general outline the fount-holder is bowl-shaped. The design consists of an exceedingly intricate foliated scroll-work springing

from a plain band, the under side curving outward and inward and contracting toward the upper edge or neck A, where the intricate scroll-work is surmounted by a series of shells 25 B, alternating with small trefoils C, the alternating shells and trefoils forming the upper configuration of the holder, the whole ornamentation of which is in the intricate style known as "rococo." 30

I claim—

The design for a lamp-fount holder as herein described and shown in the accompanying illustrations.

In testimony whereof I have signed this 35 specification in the presence of two subscribing witnesses.

ALBERT PATITZ.
